APPARATUS FOR PRODUCING SHOE SOLES
WITH TAPE ATTACHEDHerman J. Moranville, Rolla, Mo., assignor to
Johnson-Stephens & Shinkle Shoe Company,
St. Louis, Mo., a corporation of Missouri

Application August 1, 1935, Serial No. 34,132

3 Claims. (Cl. 112—130)

The invention relates to the art of shoe manufacture and consists in a novel mechanism used in the production of inner soles having tapes for attaching uppers thereto stitched to the inner sole throughout a portion of the length of the sole.

It has been customary in the manufacture of shoes of the type referred to, to mount a roll of tape upon a sewing machine and to sew a section 10 of the tape to an inner sole substantially adjacent to one edge of the inner sole, then to remove the sole from the stitcher without severing the tape and to continue sewing another section of the tape along one edge of another inner sole, 15 and so on. This operation produced a series of soles successively connected by the continuous tape, successive sections of which are attached to different soles, there being a section of unsewn tape connecting the successive soles. This 20 "string" of soles was transferred to another operator who would cut the intermediate unsewn sections of tape so as to separate the soles from each other. The soles having the tape along one edge only of each sole were then returned to the 25 stitcher and the operations described repeated in connection with the attachment of a tape along the other edge of each sole and the subsequent severing of the individual soles from the tape. This system required at least four operations to 30 produce each sole in addition to the repeated transfer of the soles between the stitcher and the cutting table. The method also resulted in a substantial amount of waste in the portions of the tape between the sewed sections.

The main object of the present invention is to 35 simplify the attachment of the tape to the soles, by reducing the number of operations and the time involved, and to eliminate the waste of unused portions of the tape.

This and detailed objects of the invention will 40 be apparent from the following description, reference being had to the accompanying drawing illustrating the apparatus used in the improved method, in which drawing—

Figure 1 is a section through a work table or 45 support showing a part of a sewing machine mounted thereon together with a tape cutting device associated with the sewing mechanism.

Figure 2 is a section and view of the cutting 50 device taken substantially on the line 2—2 of Figure 1.

Figure 3 is a top view of the cutting mechanism 55 and the adjacent portion of the work support, a sole which has been stitched being also shown.

Figure 4 is a detail section taken on the line 4—4 of Figure 1.

The sewing machine includes a work table or support 1, and a head 2 which mounts a sewing or stitching mechanism including a presser foot 5 3, a needle bar 4, and a needle 5, all of which are of familiar construction and in themselves do not constitute the present invention.

Mounted on the work support is a pair of shears including a stationary blade and handle 6 and a 10 movable blade and handle 7 pivoted thereto. The cutting edges of the blades are closely adjacent to the presser foot and needle, and the handles extend away from the blades to a part of the 15 machine which is substantially remote from the operator.

A bracket 8 mounted on the rear of the machine is provided with a pivotal mounting 9 for a bell crank lever having an arm 10 extending towards the front of the machine and terminating in a pad 11 within easy reach of the hand of the operator. The other arm 12 of the bell crank extends downwardly from the pivot 9 and has a forked end 13 which slidably receives a stud 14 20 on the upper end of a jointed finger 15 having its lower end connected to the movable shear handle 7. A tension spring 16 tends to move handle 7 to open the shears, and pressure on pad 11 applied in the direction of the arrow A tends to 25 close the shears.

A tension device for the shears is detailed in Figure 4, nut 17 providing for the adjustment of the tension and the wire spring 18 serving to hold nut 17 against accidental rotation.

A short knife 25 projecting from the upper 30 face of blade 7 facilitates cutting the bobbin thread.

Operation.—The operator starts the operation at 21 by stitching the end of the tape to the sole approximately adjacent the toe and one edge of the latter and after stitching the tape to the point 22, the presser foot is lifted and the sole slipped immediately to the rear of the presser foot with the tape in between the blades of the shears. Pressure on pad 11 severs the tape, the work is shifted to bring the bobbin thread T against knife 25, the work is turned around and a new stitching operation is commenced at 23. When this is finished, the presser foot is again 40 lifted, the sole shifted to the position shown in Figure 3, and the tape and thread again severed immediately adjacent the end of the stitching.

The sole is now complete, so far as the tape 45 affixing operation is involved, and may be taken 50

direct to the portion of the shop where the uppers are attached.

All of the tape which is used is stitched from end to end to the sole and there are no substantial lengths of tape discarded, as has been the practice heretofore.

The operation described requires no appreciable increase in the time of the sewing machine operator over and above the time required for the older method of stitching successive soles to the tape, and the time and labor involved in handling the strings of soles from the sewing machine to the cutting table and back to the sewing machine is eliminated.

Obviously, the invention is not limited to the details of mechanism illustrated, nor must all of the steps of the operation be followed in the particular order described above in order to benefit from the invention. The exclusive use of such features as come within the scope of the appended claims is contemplated irrespective of modifications which may be adopted.

I claim:

1. In a machine of the class described, a work support, a stitching mechanism including a presser foot and a needle, a head spaced above said work support and mounting said mechanism, a cutting device including a blade arranged to sever material being stitched at a point adjacent said presser foot and needle, means for moving said blade located at a point spaced from said blade and a part of the machine nearest the operator, a manually engageable element near said machine part, and an operative connection between said means and element, said element being supported from said work support and pro-

jecting forwardly of said head and spaced laterally therefrom from said stitching mechanism and said element and connection being operable independently of said stitching mechanism.

2. In a machine of the class described, a work support, a bracket thereon, a bell crank pivoted on said bracket and including an operating arm spaced substantially above said work support and extending towards the portion of the machine adjacent the operator, said bell crank including a depending arm terminating adjacent to said work support, a pair of shears having a stationary handle fixed to said work support with its blade extending towards the part of the latter normally occupied by the work, said shears having a movable handle connected to said depending arm whereby movement of said operating arm will move said movable handle to close said shears.

3. A tape cutting device applicable as a separately formed unit to a sewing machine having an elevated head and a stitching mechanism thereon and a work support, said device comprising a bracket constructed and arranged to be mounted upon said work support at a point spaced from said stitching mechanism, cooperative cutting elements carried by said bracket and arranged to project to a point adjacent said stitching mechanism, and means for actuating said cutting elements including a lever arranged to project forwardly to pass beneath the machine head and then upwardly to present a part in front of said head arranged for engagement manually by the hand of the operator.

HERMAN J. MORANVILLE.
